UNITED STATES PATENT OFFICE.

ERNEST E. MALLORY, OF LOS ANGELES, CALIFORNIA.

STOOL.

1,388,736.

Specification of Letters Patent. Patented Aug. 23, 1921.

Application filed October 22, 1920. Serial No. 418,725.

To all whom it may concern:

Be it known that I, ERNEST E. MALLORY, a citizen of the United States, residing at Los Angeles, in the county of Los Angeles and 5 State of California, have invented certain new and useful Improvements in Stools; and I do hereby declare the following to be a full, clear, and exact description of the invention, such as will enable others skilled 10 in the art to which it appertains to make and use the same.

The invention relates to improvements in seats generally, particularly the type commonly called stools.

15 The invention has for its object especially to provide means for affording impromptu or extemporaneous sitting facilities, as where provision may be required for additional seating capacity or in the absence of any 20 previous provision to that end.

Various other objects of the invention will be apparent from the following description and accompanying illustration thereof.

The invention therefore consists of certain 25 instrumentalities and features of construction substantially as hereinafter more fully set forth and defined by the appended claims.

The accompanying drawing illustrates the 30 preferred disclosure of one form of my invention wherein it will be understood that various changes and modifications as relate to the detailed construction and arrangement of parts may be made without departing 35 from the spirit or scope of the invention as embraced in the claims, and in which drawings—

Figure 1 is a side elevation of my invention.

40 Fig. 2 is a similar elevation viewing the device at right angles to Fig. 1.

Fig. 3 is a longitudinal section of the same.

Fig. 4 is a central transverse section taken 45 on the line 4—4 of Fig. 2.

Fig. 5 is a vertical section of the device collapsed or folded.

As characteristic features of my invention I constitute the stool of two general or 50 main members 1, 1^a each of these comprising two sections 2, 2^a, the same being preferably of light plate-metal and all assembled in X-shape, the convergent terminals of each of said members being pivotally connected together by a common bolt-like member or pivot 3 so as to be readily collapsible

or foldable and spread apart, the latter action serving to cause the parts to assume the stool-formation with resultant crossing legs.

The frame-sections 2, of one main member 60 1 are right-angled in transverse section, the lower and upper transverse end-portion of which sections being adapted to rest upon the surface or ground and to support the seat, at one end, respectively, as more clearly 65 appreciated later.

The sections 2^a of the other main-member 1^a are of plate-like contour as shown, and to one of these plate-like sections 2^a is connected the seat 4, which is also preferably of light-plate-metal, the connection being effected 70 preferably by providing the seat, at one end, with a loop or ring 5 freely hung thereon and adapted to freely receive and permit of a limited movement thereof upon an upbent 75 portion or tongue 6 or the seat, thus allowing ample clearance in providing for freely folding of these one upon the other when the stool is not required for use.

The opposite end of the seat 4 has freely 80 attached thereto a hook 7 which is adapted to be forcibly engaged or hooked under a downwardly depressed loop-forming portion 8 bent outwardly from and away from the plane of the seat, the hook being thus resiliently held in effective or fastened position 85 when the stool is in use. The same end of the seat 4 has suitably or freely attached thereto a ring 9 to provide for conveniently suspending the stool up out of the way when 90 not required for use.

The relatively lower portion of one of the plate-like sections 2^a and of the opposed lower portion of one of the sections 2 are 95 suitably braced together by a metallic strap-member or brace 10, one terminal of which is provided with an orifice, or adapted to form a loop, as 11 adapted to be sprung into the resilient clasp or hooked portion of a bracket 12 secured to one of said sections 2^a, 100 the other terminal of said strap-member or brace 10 forming a hook 13 adapted to be caught or sprung into a slot or aperture 14 in one of said plate like sections 2 and readily detachable in collapsing the stool, the afore-said looped terminal 11 of said brace 10 being 105 equally readily detachable from the bracket 12.

The upper and lower plate and frame sections 2^a and 2, respectively, upon the same 110 side are braced in position by a strap or brace 15, comprising two sections 15^a, 15^b,

freely connected at their distant terminals to the upper portion of the plate-section 2^a and the lower portion of the frame-section 2, respectively. The connections between said 5 distant terminals of the brace-sections 15^a, 15^b of the brace 15 and said frame section and said plate-section are preferably effected by forming one terminal of one brace-section with a hooked or curved portion, as 16, 10 which preferably engages the same slot or aperture 14 in the lower frame-section 2 into which is caught or received the hook 13 of the brace 10, and preferably providing one terminal of the other brace-section with an 15 aperture or loop 17 adapted to effect engagement with a loop 18 preferably formed integrally with, or bent-up out of the upper plate-section 2^a. The sections or members 15^a, 15^b of the brace 15 are detachably connected together by means of an interengaging hook 15^b and staple 15^c formed upon 20 said members, respectively, as seen in Fig. 3.

Preferably a wooden key or wedge member 19 which, however, may be of other suitable 25 material, is provided for the effective retention of the several parts of the stool in stable position when extended or set up for use, said wedge being inserted intermediate the preferably pivotal or axial bolt member 3 30 and the main sectional-plate member 1^a. The wedge or key member 19, itself, is retained in slideable or adjustable position by means of what may be termed a keeper or clamp 20 adapted to clamp the key or wedge in place 35 to said member 1^a, said clamp being adapted to be suitably clenched in position to one of the sections of the latter and offset therefrom to receive the wedge or key thereunder. The clamp 20 is preferably narrowed or tapered 40 longitudinally and has a longitudinal slot 21 extending considerably the length thereof and having applied thereto a binding screw 22 manipulatable in said slot in clamping the wedge or key firmly in position upon the 45 plate-sections, under the pivotal bolt, across the point of convergence between the plate-sections in providing for the longitudinal adjustment of the wedge accordingly as it may be desired to fold or open up the stool. 50 In unfolding the collapsed or folded stool, it is only required to unlatch the sections 15^a, 15^b of the member 15 one from the other; next, disconnect the brace 10 from the hook 12 of the lower member 2^a; next, slide 55 the member 19 upwardly past the rod 3; finally, disconnect member 7 from the downwardly depressed loop 8 of the seat 4, the latter thus being allowed to swing inwardly together with the now already or previously 60 released mentioned parts, into compactly folded or nested position.

It is thought that, from the foregoing explanation of the construction, arrangement and operation of parts together with the accompanying illustration, the use and advan-

tages of my invention will be clearly appreciated.

Having thus described my invention I claim:

1. A device of the type described including main-members, each of these members comprising sections having their meeting or convergent ends pivotally connected to a common pivot, a seat-member, means at the rear edge of said seat-member integral therewith, means integral with one of said main-member sections and means forming freely movable connection between the aforesaid seat-member and said main-section. 70

2. A device of the type described, including frame and plate-like main members, each of these members comprising sections having meeting or convergent ends pivotally connected to a common pivot, a seat-member, means at the rear edge of the seat member integral therewith, means integral with one of said main-member sections, and means forming freely movable connection between the said seat-member integral means and said main-section integral means. 80

3. A device of the type described, including main members, each of these members comprising sections having meeting or convergent ends pivotally connected to a common pivot, a seat-member, said seat-member having freely and detachable connections with said main members, respectively, a sectional bracing member between main-member sections, and a bracing member between opposite lower main-sections, the sections of the first referred-to bracing member being detachably connected to one of said lower main-sections. 90

4. A device of the type described, including main members, each of these members comprising sections having meeting or convergent ends pivotally connected to a common pivot, a seat-member, means for effecting connection between one end of said seat and one of said main members to allow 105 freely turning the seat thereon, means of connection between said seat and the opposed member of the other main member to provide for readily detaching said seat-member therefrom, and a slideable member 110 arranged between said pivot and one of said main-members, adapted to effect the stable retention of the parts in normal or extended position. 115

5. A device of the type described, including main members, each of these members comprising sections having convergent ends pivotally connected to a common pivot, and a seat-member, means for effecting connection between one end of said seat-member 120 and one of said main members, means effecting ready detachability of said seat-member from the opposed main member, and a wedging member adapted to be inserted between said pivot and one of said main mem- 125 130

bers for effecting the stable retention of the parts in normal or extended position.

6. A device of the type described, including main members each comprising sections having convergent ends pivotally connected to a common pivot, a seat-member, means effecting connection between said seat-member and said main members, a slideable wedging member adapted for insertion between 10 said pivot and said main members, a sec-

tional bracing member between main-member sections and a bracing member between opposite lower main-member-sections, the sections of the first referred to bracing member being detachably connected together, 15 said second bracing member being detachably connected to one of said lower main member sections.

In testimony whereof, I affix my signature.
ERNEST E. MALLORY.
